UNITED STATES PATENT OFFICE.

EDWARD P. HUNT, OF BUFFALO, NEW YORK.

PUZZLE OR GAME APPARATUS.

1,266,271.

Specification of Letters Patent. Patented May 14, 1918.

Application filed February 20, 1917. Serial No. 149,766.

To all whom it may concern:

Be it known that I, EDWARD P. HUNT, a citizen of the United States, residing at Buffalo, in the county of Erie and State of New York, have invented new and useful Improvements in Puzzles or Game Apparatus, of which the following is a specification.

This invention relates to a novel and attractive game apparatus or puzzle.

10 The object of the invention is to provide an apparatus of this character designed to imitate or represent the shooting of soldiers in the trenches and adapted to afford entertainment by calling for the exercise of a certain amount of the player's skill in playing 15 the game or solving the puzzle.

The game or puzzle comprises a board provided with a plurality of intersecting grooves or channels representing trenches, 20 at the outer ends of which are arranged toy soldiers, and a revolving gun adapted to sweep over the trenches and receive projectiles for knocking down the soldiers.

In the accompanying drawings:

25 Figure 1 is a perspective view of my improved game apparatus. Fig. 2 is a sectional view of a portion of the game board showing the means of mounting the toy soldiers. Fig. 3 is a vertical section taken 30 on line 3—3, Fig. 1.

Similar characters of reference indicate corresponding parts throughout the several views.

1 represents the base of the game board 35 which is constructed of cardboard, wood or other appropriate material, and 2, 3, indicate the side and end walls thereof.

Arranged in the base 1 of this game board are a plurality of intersecting grooves 40 or channels 4, 5, 6, 7, representing military trenches, there being preferably four sets each comprising two grooves in parallel relation with each other. As shown in the drawings, these trenches have the appearance of an eight-pointed star, which is produced by describing these grooves around the central octagonal portion area 8. At the intersection of these grooves, or at the eight points of the star, are formed enlargements 45 9 which are provided with depressions or pockets 10.

The trench-grooves may be carved or otherwise cut if the base 1 is constructed of wood, while if constructed of metal or thick cardboard, the same may be stamped. 55

Located at the outer junctions of the intersecting trench-grooves are figures representing soldiers 11, 12, 13, 14, 15, 16, 17, 18, one man being stationed at each point of the star, making eight in all. Each of these 60 soldiers is rigidly mounted on a platform 19 arranged in alinement with or opposite the junction of the adjacent intersecting grooves. Each platform is pivotally mounted or hinged on a base plate 20 riveted or 65 otherwise secured to the game board and having vertical lugs 21 which receive a horizontal pin or pintle 22 to which the rear end of said platform is secured. The latter extends over the adjacent enlargement 9 70 and the front end of the platform is curved upwardly so as to extend a short distance above the surface of the boards, as clearly shown in Fig. 2.

23, 23, indicate the barrels of a duplex 75 gun for shooting balls or projectiles 24 at the toy soldiers. This gun is suitably supported on a revolving base 25 pivoted at 26 to the central portion 8 of the game board. These barrels are inclined to slope toward 80 the trenches, so that the projectiles introduced into their open rear ends will roll by gravity into the trenches and upset the toy soldiers by striking the upturned ends of the platforms 19. The barrels of the gun 85 are parallel with each other and spaced to register with the parallel trench-grooves of each set.

Each of the toy soldiers 11—18, inclusive, is preferably mounted closely to the fulcrum 21 of its platform 19, to bring its center of gravity in close proximity to said fulcrum, thereby causing the soldiers to fall backward readily under the impact of a comparatively light projectile. 95

The object of the game or puzzle is to knock down seven of the eight soldiers consecutively with only seven projectiles, thus leaving but one soldier standing behind one of the gun barrels when the game is over. 100 To attain this object, it is necessary always to have a soldier behind one of the gun-

barrels, in order to shoot at another soldier. Furthermore, after one soldier has been shot or knocked down, it is necessary to turn or train the gun to a position to knock down 5 the soldier who last shot the gun, and so on until seven men are down.

To play the game, all of the soldiers are placed in their upright position ready to be knocked down by a projectile. The player 10 then revolves the gun about its pivot to any desired position, bringing it in alinement with a pair of trenches and pointing one of its barrels at the soldier he wishes to shoot. He then places in the elevated end of said 15 barrel, a ball or projectile which rolls down into the desired trench and is directed by the latter toward the upturned front end of the platform on which the soldier is mounted, the projectile striking said end and tipping the platform far enough to cause the soldier to fall on his back. After upsetting the soldier, the projectile drops into the corresponding pocket 10 and remains there until the end of the game. The player next 20 turns the gun to a position which will permit him to knock down the soldier who last fired the gun, being careful to see that there is a standing soldier behind the gun and not a previously-fallen one. In the position of 25 the parts shown in Fig. 1 of the drawings, the player is assumed to have started by firing at and upsetting the soldier 16, and then to have turned the gun to the position shown and upset the soldier 11, who had previously 30 fired at the soldier 16. The player next turns the gun to a position to knock down the soldier 14 who had just previously fired the gun. This process is continued until 35 only one soldier remains standing, signifying that the game is won or the puzzle solved.

Although I have shown a double-barrel gun, I do not wish to be limited to that construction, as the game can be carried out successfully by the use of a single-barrel gun. By using the double-barrel gun, the player has a choice as to the barrel with which he prefers to shoot, that is, either from the right or left barrel. If desired, the game 50 board may also be modified within the scope of the appended claims without departing from the invention.

I claim as my invention:

1. In a game apparatus or puzzle, a game 55 board having a central area, a plurality of grooves extending in different directions from said area, movable objects arranged in line with said grooves, and a gun mounted on the game-board and revolvable about said 60 central area for shooting projectiles into any of said grooves from their inner toward their outer ends.

2. In a game apparatus or puzzle, a game

board having a plurality of intersecting trench-grooves arranged in the form of a star, objects representing soldiers located at the points of said star and pivotally mounted on said board, and a revoluble gun arranged centrally of the star and adapted to shoot projectiles into said grooves. 65

3. In a game apparatus or puzzle, a game board having a plurality of trench-grooves, platforms located in line with said grooves and hinged to said board, figures secured to said platforms, and a gun mounted on the 70 game board and having a barrel capable of assuming positions in line with said grooves for shooting projectiles into the same. 75

4. In a game apparatus or puzzle, a game board having a plurality of parallel sets of intersecting grooves arranged in the form of a star, figures representing soldiers located at the points of said star and hinged to said board, and a revoluble gun mounted centrally of said star and having downwardly-inclined barrels arranged in spaced parallel relation with each other and adapted to be brought into alinement with a set of said parallel grooves for shooting projectiles into the same. 80

5. In a game apparatus or puzzle, a game board having a plurality of trench-grooves, platforms located in line with said grooves and hinged to said board, each of said platforms having an upturned front end, figures 95 mounted on said platforms, and a gun movably mounted on the game board and adapted to shoot projectiles into said grooves. 90

6. In a game apparatus or puzzle, a game board having a plurality of parallel sets of intersecting grooves arranged in the form of a star, pockets located at the points of said star, hinged platforms mounted on said board and extending over said pockets, each of said platforms being provided with an 100 upturned front edge adapted to be struck by a projectile, figures representing soldiers secured to said platforms, and a revoluble gun mounted centrally of said star and having a downwardly-inclined barrel adapted 110 to be brought in alinement with said grooves. 105

7. A puzzle or game apparatus, comprising a board having a gun revolvably mounted on said board, a plurality of movable figures stationed on said board about said 115 gun, and projectiles adapted to upset said figures, the number of said projectiles being one less than the number of said figures.

8. A puzzle or game apparatus, comprising a board having a plurality of trench-grooves, movable military figures stationed in line with said grooves and each adapted to be felled by a single shot, a gun, and projectiles adapted to upset said figures, the number of said projectiles being one less than the number of said figures. 120

125

9. A puzzle or game apparatus, comprising a board having intersecting pairs of parallel trench-grooves arranged in the form of an eight-pointed star, eight figures representing soldiers, one stationed at each point of said star, said figures being hinged to said board, a revoluble gun arranged centrally of said star and having a pair of parallel barrels spaced apart to correspond to the spacing of said pairs of trench-grooves, and seven projectiles each adapted to be shot toward one of said figures.
